Patented Aug. 3, 1920.

UNITED STATES PATENT OFFICE.

MERL R. PONTIUS AND ALVER L. WEST, OF ELDORADO, KANSAS.

SAND-REEL SUPPORT.

1,348,734.

Specification of Letters Patent. Patented Aug. 3, 1920.

Application filed May 31, 1919. Serial No. 301,005.

To all whom it may concern:

Be it known that we, MERL R. PONTIUS and ALVER L. WEST, citizens of the United States, residing at Eldorado, in the county 5 of Butler and State of Kansas, have invented new and useful Improvements in Sand-Reel Supports, of which the following is a specification.

This invention relates to improvements in 10 well-drilling rigs and more particularly to the structure of the sand reel and the invention has for its object to provide a structure of this character constructed entirely of metal thereby to increase the rigidity and 15 durability of the rig and possessing such novel features of construction as will permit of the entire structure being readily taken apart for convenience in transportation.

Another object is the provision of an improved support for sand reels which will 20 permit of swift and convenient adjustment of the supporting shaft in order to bring the friction pulley into and out of engagement with the driving wheel, as desired.

With these and other objects in view as 25 will appear as the description proceeds the invention comprises the novel features of construction combination of elements and arrangement of parts which will be more fully 30 described in the following specification and set forth with particularity in the claim appended hereto.

Figure 1 represents a fragmental side elevation of the rig illustrating the improved 35 sand reel support in detail.

Fig. 2 represents a front elevation of the reel and improved support therefor,

Fig. 3 represents a fragmental longitudinal sectional view through one of the 40 supports for the wheel shaft, and

Fig. 4 represents an end elevation of the relatively stationary bearing.

Referring to the drawing in detail, wherein similar reference numerals designate corresponding parts throughout the several 45 views the numeral 5 indicates generally the relatively stationary bearing standard which is supported by an integral base plate 6 upon the supporting platform of the drilling rig and is provided in its upper portion 50 with a transverse aperture 7 receiving the top and bottom bearings 8 and 9 respectively which are of such size as to admit of a relatively wide range of adjustment thereof in 55 planes at right angles to each other within the opening 7 in the bearing standard. The

lower bearing member is adjustably supported by and clamped between three screws 10 two of which are disposed horizontally and arranged in diametrically opposed relation in the opposite sides of the opening 7 and the third screw of the group is disposed vertically and threaded in an aperture formed in the lower part or wall of the opening 7. The inner terminals of the 60 several supporting screws are engaged at spaced intervals with the external surface of the lower bearing member 9 and, by proper manipulation of the screws the position of the lower bearing member 9 may 65 be varied as desired within the opening 7 and, as will be readily appreciated, lock nuts or other suitable types of locking devices are employed for securing the adjusting screws in the desired positions. The upper 75 bearing member 8 is arranged above the bearing member 9 and confined between longitudinal ribs 11 formed thereon and is maintained in adjusted position by a screw 12 threaded in an internally threaded aperture formed in the top wall of the opening 7.

The inner or bearing surfaces of the members 8 and 9 are formed with opposed concavities 13 shaped conformably with and 80 confining the spherical head 14 formed integrally with one terminal of the hand reel shaft 15, the body portion of which latter is of less external diameter than the internal diameter of the bearing formed by the members 8 and 9 whereby the axial position of 85 the shaft 15 with relation to the axis of the bearing may be varied, as desired.

The opposite terminal of the hand reel shaft 15 is supported in a movable bearing 95 designated generally by the numeral 16 and which is pivotally supported upon a pivot pin 17 secured in the opposite ears 18 of a base plate 19 arranged upon the supporting platform of the drilling rig at a point removed from the relatively stationary bearing member 5.

The movable bearing 16 is in the form of a lever which is constructed in two sections 20 and 21 having their adjacent terminals flanged and detachably connected as at 22 105 by bolts or equivalent fastening devices. By constructing the lever in two parts in this manner, the parts may be readily disassembled for convenience in transportation. The sections or parts 20 and 21 are formed with an 110 aperture 7^a similar in size and shape to the aperture 7 in the relatively stationary bear-

ing standard 5 and receiving superposed bearing members 8^a and 9^a which are also identical in construction to the bearing members 8 and 9 except that they are formed with a plane bore for engagement with the plane external surface of the terminal of the sand reel shaft 15 with which they are engaged. The lower bearing member 9^a is supported in adjusted position by a series of angularly disposed screws 10^a and the upper bearing member 8^a is adjustably supported in position by a screw 12^a.

In applying the invention to use, the shaft 15, as usual, is disposed adjacent the driving wheel a fragment of which is illustrated in Fig. 1 and a friction pulley 23 is supported upon the shaft 15, and by proper manipulation of the lever 20 is movable into and out of engagement with the circumferential edge of the driving wheel in order that the rotary movement of the latter may be transmitted to the shaft 15 at the will of the operator, in order to actuate the sand reel indicated at R in dotted lines in Fig. 2. As is clearly evident, the lever or post 16 is movable outwardly and inwardly with relation to the driving wheel upon the pivot pin 17, the spherical head 14 at the terminal of the shaft 15 engaging in the con-30 cavities 13 of the superposed bearing mem-

bers 8 and 9 permitting a limited swinging movement of the shaft sufficient to permit of the desired adjustment of the friction pulley 23.

What we claim is:

In a well drilling rig constructed entirely of metal, a drive wheel, a stationary and a pivoted standard, each having an opening to receive a shaft bearing, a sectional shaft bearing mounted in each opening, said opening being of a size to permit a relatively wide range of adjustment of the bearing therein, means for supporting each bearing in adjusted position, the pivoted standard being composed of detachably connected sections separably connected at the opening therein, a sand reel shaft mounted in said bearings, a friction pulley carried by said shaft, a ball and socket joint between the shaft and the bearing of said stationary standard to allow a limited swinging movement of the shaft sufficient to permit of the adjustment of the friction pulley carried by the shaft to cause it to engage said drive wheel.

In testimony whereof we affix our signatures hereto.

MERL R. PONTIUS.
ALVER L. WEST.
